UNITED STATES PATENT OFFICE.

JAMES ROBERT PILSON AND LOUIS ZOLL, OF VANGUARD, SASKATCHEWAN, CANADA.

AUTOMATIC DOORCHECK.

Application filed March 13, 1922. Serial No. 543,366.

To all whom it may concern:

Be it known that we, JAMES R. PILSON and LOUIS ZOLL, both subjects of the King of Great Britain, and both residents of Vanguard, in the Province of Saskatchewan and Dominion of Canada, have invented certain new and useful Improvements in Automatic Doorchecks, of which the following is a specification.

10 This invention relates to improvements in automatic door checks, and has for its objects to provide a means of automatically closing a door, to provide a means whereby a door may be held in open position, to provide a spring-actuated element designed to be carried by the door frame and be actuated by an arm connected to the door.

Further objects are to provide an automatic door check which consists of two L-shaped elements, one being slidably mounted on the other and carrying a cam race, a vertical shaft extending between the two L-shaped members and carrying a cam member designed to be held in engagement with the cam race by means of a spring coiled around the shaft.

Further objects are to provide a means whereby the door may be held open at any desired angle, and which consists of providing a corrugated surface on the cam race.

Still further objects are to provide an automatic door check which is simple in construction, not liable to go out of repair, and generally to adapt the several parts to better perform the functions required of them.

In the drawings:

Figure 1 is a perspective view of the improved automatic door check.

40 Figure 2 is a plan view of the same.

Figure 3 is a longitudinal section.

Figure 4 is a perspective view of the vertical shaft and cam member.

Figure 5 is a perspective view of the sliding element.

Figure 6 is a front perspective view of the cam race member.

Figure 7 is an enlarged sectional detail of an alternative form of cam race to be used for heavy doors.

Figure 8 is a front perspective view of an alternative form of cam race designed to be used to retain the door in an open position.

Figure 9 is a longitudinal section of the form of cam race shown in Figure 8.

In the drawings, like characters of refer-

ence indicate corresponding parts in all the figures.

Referring to the drawings:

A represents the improved automatic door check which consists of an inverted L-shaped member 10 provided with a threaded orifice 11 which engages the shank of a tightening bolt 12 which extends through a longitudinal slot 13 provided in the vertical arm of an L-shaped sliding element 14. The two arms of the sliding element 14 may be reinforced by means of the braces 15, and the horizontal arm thereof is provided with a sleeve 16 which is square in cross section, as clearly shown in Figure 5.

The L-shaped element 14 is designed to be securely held to the L-shaped member 10 by means of a tightening bolt 12 co-acting with a second means, which will be described hereinafter. Extending through the bore 17 of the sleeve 16 is a vertical shaft 18, the upper end of which extends through an orifice provided in the horizontal arm of the L-shaped member 10, and the two ends of the vertical shaft 18 are each formed with a screw-threaded shank 19 and 20.

Engaging the top end of the vertical shaft 18 is an enlarged apertured portion 21 of an arm 22 which is connected at its free end to a small connecting arm 23, as shown at 24, and the arm 23 has its free end suitably bolted to a clamping member 25 which consists of a disc provided with a pair of apertured ears according to the well-known construction. This disc or clamp 25 is designed to be fastened to the door in connection with which this automatic check is to be used.

Inserted on top of the enlarged portion 21 and engaging the threaded shank 19 at the top of the vertical shaft 18 is a plate 26 which is offset as at 27, and the offset portion is provided with a square orifice designed to register with a similar orifice 28 provided in the horizontal arm of the L-shaped member 10, and which square orifices are designed to be engaged by a long bolt 29 formed with a head 30 which is square in cross section.

The lower end of the bolt 29 is threaded and extends through an orifice 31 formed in the horizontal arm of the L-shaped element 14, and which is designed to be securely held thereto by means of a winged nut 32, thus co-acting with the tightening bolt 12 to secure the sliding element 14 in

a predetermined position relative to the L-shaped member 10.

A C-shaped element or arm 33, which has its two ends apertured and designed to engage the threaded shanks 19 and 20 of the vertical shaft 18 is provided, as shown in Figure 1 of the drawings. The C-shaped arm 33 extends through a slot 34 provided in the arm 22 and is thus caused to move together with the arm 22 when the same is caused to pivot by the movement of the door.

The arm 33 is retained on the shank 19 by means of a washer 35 and nut 36, while its lower end is retained on the shank 20 by the nut 37. The vertical shaft 18 is provided intermediate of its length with a cam member 38 which may be keyed thereon or formed integral therewith, as desired. The cam member may be preferably formed of a disc provided with a depending lug or cam proper as shown at 39.

A cam race is provided on the top edge of the sleeve 40, which is formed with a square bore 41 designed to be engaged by the square sleeve 16 which is formed on the horizontal arm of the sliding element 14. The top edge of this sleeve 40, which is carried by the horizontal arm of the element 14, has a portion which is horizontal as shown at 42 and an oblique part 43 of V-shape and formed with a sudden drop 44 which is located at the apex of the V.

This cam race is designed to co-act with the lug or cam proper 39 of the cam member 38 on the operation of the door.

Coiled around the vertical shaft 18 and bearing at its lower end against the top face of the cam member 38 is a coil spring 45 which bears at its top end against a washer 46 bearing against a horizontal member of the L-shaped member 10 and provided with ball bearings 47. If desired, the coil spring 45 may be suitably housed by a covering 48 which is provided with a telescoping portion 49 designed to slide over the portion 48 when the spring 45 is compressed, owing to the action of the cam 39 on the cam race 43.

If desired, the horizontal arm of the L-shaped member 10 may be reinforced by means of the braces 50 similar to the braces 15 used in reinforcing the arms of the L-shaped element 14.

When this improved automatic door check is in use, the L-shaped member, which carries the working parts of the automatic check, is fastened as at 51 to the door frame or adjacent to the door, and the clamp 25 carried by the arms 22 and 23 is fastened to the door. When the arm 22 is rigidly connected to the vertical shaft 21 and is in engagement with the C-shaped arm 33, which is rigidly connected to the threaded shanks 19 and 20 of the vertical shaft, it

will be obvious that, on the arm 22 being pivoted by the operation of the door, the vertical shaft 18 will also be rotated at the same angle and the cam member 38, which is integral or keyed to the vertical shaft 18, will be caused to rotate, and the lug 39 thereof ascending the incline 44 of the cam race 43 will raise and thereby compress the spring 45.

When the door is released, the lug 39 of the cam member will slide down on the incline 44 and will be forced down by the action of the expanding spring 45. The sudden drop 44 is provided in the cam race 43 so that the lug 39 will suddenly drop to its normal position and force the door to close. When it is desired to retain the door in open position, the door is forced open until the lug 39 comes into engagement with the horizontal portion 42 of the cam member, when the spring 45 will be held in compressed position on account of the cam member being unable to fall back to its normal position.

In the case of very heavy doors, the cam lug 39 may be formed so as to extend to the side of the side of the cam sleeve 40, and a roller 52 will be provided on the inner side of the lug 39 which will be in engagement with the inclined surface of the cam race 43.

When it is desired to retain the door in open position without having it wide open, a special cam race is formed which consists of the sleeve 53 which is exactly similar to the sleeve 40 and is formed at its upper edge with an inclined cam shank 54 provided with corrugations 55. In this case, when the roller 52 has been caused to ascend the incline 54 of the cam race and is in bearing engagement with one of the corrugations, it will be obvious that the door will be retained in the open position, as the force of the spring 45 will be insufficient to force the cam to be disengaged from the corrugations 55.

As many changes could be made in the above construction and many apparently widely different embodiments of our invention within the scope of the claims, constructed without departing from the spirit or scope thereof, it is intended that all matter contained in the accompanying specification and drawings shall be interpreted as illustrative and not in a limiting sense.

What we claim as our invention is:

1. An automatic door check comprising an L-shaped member, a vertical sliding element mounted on the vertical arm of the L-shaped member having a lateral extension, a vertical shaft extending through the extension and the horizontal arm of the L-shaped member, a cam member on the shaft intermediate of the length thereof, a cam race on the extension loosely engaging the shaft, a coil spring on the shaft, an arm rigidly connected to the shaft designed to be fastened to a door, and a C-shaped element rigidly engaging the

shaft and extending through a slot in the arm.

2. An automatic door check comprising a supporting member, a sliding element mounted on the supporting member and having a lateral extension, a shaft extending through the extension and the supporting member, a cam member on the shaft, a cam race on the extension, loosely engaging the shaft, a roller on the cam member engaging the cam race, a coil spring on the shaft, an arm rigidly connected to the shaft designed to be fastened to a door, and a C-shaped element rigidly engaging the shaft and extending through a slot in the arm.

3. An automatic door check comprising a supporting member, a sliding element slidably mounted on the supporting element

through a slot and pin arrangement, a shaft extending through the extension and the supporting member, a cam member on the shaft, a cam race on the extension, loosely engaging the shaft, a roller on the cam member engaging the cam race, a coil spring on the shaft, an arm rigidly connected to the 20 shaft designed to be fastened to a door, and a C-shaped element rigidly engaging the shaft and extending through a slot in the arm.

In witness whereof we have hereunto set 25 our hands in the presence of two witnesses.

JAMES ROBERT PILSON.
LOWIS ZOLL.
